United States Patent Office.

HORACE FENN, OF PLYMOUTH, CONNECTICUT.

Design No. 3,769, dated November 30, 1869.

DESIGN FOR A TRADE-MARK.

The Schedule referred to in these Letters Patent and making part of the same.

To all whom it may concern:

Be it known that I, HORACE FENN, of Plymouth, in the county of Litchfield, and State of Connecticut, have invented a new Design for Trade-Mark; and I do hereby declare the following, when taken in connection with the accompanying drawing, to be a full, clear, and exact description of the same, and which said drawing constitutes part of this specification, and represents my design.

This invention relates to a design for a trade-mark,

specially designed for saws, but with intent to use for general purposes; and the design consists of a hound's head, with the word "Niagara" over the same, as fully shown in the accompanying drawing.

I claim, as my invention, the design for trade-mark, as shown.

HORACE FENN.
